US0D1085151S

(12) **United States Design Patent** (10) **Patent No.:** **US D1,085,151 S**
(45) **Date of Patent:** **** Jul. 22, 2025**

(54) **DISPLAY SCREEN PORTION WITH USER INTERFACE**

- (71) Applicant: **Zafran Security LTD**, Tel Aviv (IL)
(72) Inventors: **Snir Havdala**, Tel Aviv (IL); **Omri Avital**, Tel Aviv (IL)
(73) Assignee: **Zafran Security LTD**, Tel Aviv (IL)
(**) Term: **15 Years**
(21) Appl. No.: **29/912,263**
(22) Filed: **Sep. 15, 2023**
(51) LOC (15) Cl. **14-04**
(52) U.S. Cl.

(57) **CLAIM**

The ornamental design for a display screen portion with user interface as shown and described.

DESCRIPTION

The FIGURE is a front view of a display screen portion with user interface showing our new design.

The outer broken lines illustrate a portion of an environmental display screen and portion of display which form no part of the claimed design. The remaining broken lines illustrate environmental portions of the display screen and portions of the user interface which form no part of the claimed design.

1 Claim, 1 Drawing Sheet
